AUTOMATIC TRAIN PIPE CONNECTER

Joseph Robinson, New York, N. Y.

Application February 25, 1935, Serial No. 8,092

13 Claims. (Cl. 285—58)

This invention is an improvement on the constructions shown in my co-pending applications Serial #754,889 and #755,831 filed November 26th, 1934, and December 3rd, 1934, respectively.

5 Among the objects of my invention is to provide an improved coupling head for automatic train pipe connectors which, though light and compact, will have an exceptionally wide gathering range in both the lateral and vertical directions, and in which improved means for removably anchoring a train pipe hose to the head, and for protecting such anchoring means, is provided.

10 Other objects and advantages of my improvement will appear from the following description and in the accompanying drawings in which

Figure 1 is a front elevation of my improved coupling head as viewed from a position at a right angle to the plane occupied by the coupling face of the head;

15 Figure 2 is a side elevation of the construction shown in Figure 1 as viewed at a right angle to the longitudinal center line of the gasket assembly;

20 Figure 3 is a sectional plan view taken on approximately the line 3—3 of Figure 1. In this view my improvement is seen in the position it occupies when installed;

Figure 4 is a rear view of Figure 2;

25 Figure 5 is a sectional detail, on reduced scale, of the means for removably securing the steam hose to the coupling head. This view is taken on the line 5—5 of Figure 2 and

Figure 6 is a rear end view of Figure 5.

30 It will be understood that any suitable means may be employed for yieldingly supporting my improved coupling head with respect to the car or car coupler. Preferably the supporting means should be designed to prevent undue rotation of the coupling head about the longitudinal axis of 35 the connector. Such a support is shown in my co-pending application, Serial No. 754,889, filed November 26, 1934.

35 My improved coupling head A comprises a vertically disposed flat base 10, which in front view has the general outline of a wide letter V. The base is disposed obliquely to the longitudinal direction of the connector, as shown particularly in Figure 3, and is considerably longer or wider than it is high. At the top of one end the base 40 is provided with a centering seat 11 and at the top of the other end it is provided with a complementary part-spherical ball or pilot lug 12, the seat and the lug being disposed on opposite sides of the vertical center of the head and in the same horizontal plane. Located on the transverse cen-

ter of the head, and below, though not necessarily below, the horizontal center of the seats 11—12, I provide a housing B which extends rearwardly away from the rear of the head. The housing is open at one side to receive a standard 5 hose fitting 14 having an enlarged gasket carrying end 15 which, as shown, rests in and projects through an opening formed in the head centrally of the housing. A suitable spring retained plunger pin 16 operates through bearings in the housing and through a lug 17 on the rear side of the fitting to removably retain the fitting in place. Formed integral with or otherwise secured to the rear side of the housing I provide a threaded shank 18 or other suitable means for attaching 10 my improved coupling head to a suitable support C. To give strength and rigidity, without excessive weight, to the base 10 of my improvement I turn the upper and lower edges thereof rearwardly to provide a flange 19, and I extend the 15 upper wall 20 of the housing laterally to the outer end 25 of the coupling head A as shown particularly in Figure 4. Reaching from the housing laterally to the centering seat 11 I provide a further reinforcing rib 21, and at 22 another 20 which extends from the housing B upwardly along the back of the base 10.

25 It will be noted that a part of the lower side or bottom 23 of my improved coupling head lies in the horizontal plane for a short distance on 30 either side of the vertical center of the head, and thence flares upwardly ending in the relatively narrow extremities 24—25 which give the base 10 the heretofore stated general shape of a flat letter V. On one side of the vertical center line 35 the head is provided with a forwardly extending downwardly and outwardly flaring guiding prong or wing D. In the present embodiment of my invention the upper face of this guide conforms to the outline of the lower side of the base to which 40 it is secured. The guide is preferably formed integral with the base though it may be otherwise secured thereto if desired. Its function primarily is to guide opposing heads into substantial alignment under conditions of vertical and 45 lateral variation. The final and accurate aligning is performed by the pilot lug 12, which may be of any shape and construction desired, entering the centering seat 11, which may be of any complementary shape and construction desired. The portion 26 of the wing base serves as 50 a rest or seat for the complementary surface 23 of an opposing head when coupled or during the act of coupling. But as stated, the accurate final alignment of the gaskets 27 of opposing heads is 55

done by the guiding lug or ball member 12 and the centering seat 11. These guiding parts serve also, in cooperation with the forward thrust of the support C to hold the heads when coupled against relative shifting. To satisfactorily secure this interlocking effect it is not necessary that the part-spherical pilot member 12 shall extend away from the face of the coupling head more than a short distance in order for the pressure of the thrust spring which forms a part of the supporting means C to create a firm interlock of these parts. It will be observed that the centering seat 11 comprises a plurality of inwardly projecting rugged lugs 29, the front faces 15 29 of which are machined to the curve of the machined face of the pilot member 12, and that between these lugs openings or ways 30 are provided to prevent the accumulation in the centering seat of any foreign substance which might 20 interfere with the proper registering of the parts.

By reason of the oblique inclination of the base 10 of my improved coupling head (see Figure 3) such base, in itself constitutes a member for gathering the heads into alignment under lateral displacement. During this gathering act the low part-spherical centering lug 12 slides along the front face of the base 10 of an opposing head toward, and finally into, the centering seat 11 of such head. The proportion and shape of this centering member 12 is such that in event it strikes against or slides across the gasket 27 no damage to the gasket will result. It will be observed that the guide D projects forwardly of the base 10 at substantially a right angle to the base for a considerable distance before it flares laterally, a conformation which may of course be varied at will to best suit conditions. The inner or vertically disposed edge 31 of the guide D serves to shift the opposing heads laterally into substantial alignment under some conditions before the bases 10 of opposing heads engage. When one coupling head is higher than another, on substantially a straight track, the guide D engages the portion 23 of the opposing head and lifts the centering members 11-12 into the area of their guiding or centering range. If such engagement occurs under conditions of extreme vertical and lateral disalignment combined, then the forward lower part of the guide D will engage high up on the inclined surface 32 of the head. From this point the opposing heads will be carried into alignment. The angularity of the base 10 with respect to the longitudinal direction of the connector will, as aforesaid, cause opposing bases to also act as lateral guides under this condition. Thus the base 10, or that portion of it which lies to the right of the vertical center line of the head, may be said to constitute a vertically flaring forwardly extending or obliquely disposed prong E for cooperating with the wing D to accomplish lateral and vertical alignment of the head, while that part of the base which lies to the left of the center line of the head may be said to constitute a rearwardly extending or obliquely disposed guiding member F for cooperating with the guiding prong E and wing D to generally align mating heads under conditions of lateral displacement, the final act of accurate alignment being performed by the cooperating parts 11 and 12. It is not indispensably necessary that the guide D extend in width to the outer point or end 24 of the head A. If desired the wing may be much narrower than shown, and an opening or openings 32a may be formed in it and in the base 10 at the point of

juncture between the guide D and the base for the purpose of providing an outlet for such foreign substances, as for instance, snow and ice, that might tend to accumulate on the base of the guide.

One or more ports for connecting the train lines through my improved head, may be provided. In its present embodiment I show the head provided with two such ports placed one above the other with their gasket faces at a right angle to each other. The upper port receives the fitting 14, which fitting preferably projects slightly through the head to form a bearing for the latter. The lower port, which includes a suitable housing or bracket 33, is formed integral with or is otherwise secured to the base 10 and the housing B and wing D. The front face of this housing is perforated and lies approximately in the plane of the vertical center line of the head. In it I removably mount a suitable steam hose fitting G which carries at its forward end a flexible or oscillating gasket 34, the face of which, if the gasket is of non-resilient material lies in the plane of the vertical center line of the head, a rise or lug 35 being provided on the vertical edge 31 of the guide D to protect the gasket against the damage in coupling further than is naturally done by the oblique arrangement of the coupling head. To removably secure the conduit G in place I provide brackets or bearings 35a formed integral with or otherwise secured to the under side of the guide D or the base A. A rugged steel plunger or thrust pin H is slidingly mounted in bearings in these lugs and projects into or against a lug or bearing 36 formed on one side of the conduit G. A wing-nut I or other suitable power means is threadingly mounted on the thrust pin between two of the bearings or brackets 35 as shown, the arrangement being such that rotation of the nut in one direction drives the pin forwardly against the fitting G and forces the annular shoulder 37 of the fitting rigidly against a wall of the housing 33, while rotation in the opposite direction draws the pin out of engagement with the fitting and releases the latter. To prevent rotation of the pin I provide it with an elongated flat head 38 which occupies a complementary opening or groove in the rear bracket 35a as shown particularly in Figure 6. This arrangement not only permits removal and replacement of the gasket 34 while the connector heads remain coupled, but also provides power means for forcing non-resilient gaskets into fluid tight engagement when the fitting G is replaced in the head after removal. Lateral shifting of the heads one on the other when one gasket is forced hard against another, is prevented by a suitable plunger lock operating through bushed bearings 39 and 40 of the base 10. A suggested suitable form of such lock is shown and described in my co-pending application, Serial No. 741,987, filed August 29, 1934. Inasmuch as the direction of fluid travel through the conduit G is at a right angle to the longitudinal direction of the bearings 39-40, the pressure of the fluid will be received by the locks that operate through these bearings. In this manner the considerable force set up by this pressure, which tends to kick coupled heads apart, is removed from the buffer spring that forms a part of the support C. Further removal of pressure on the buffer spring is secured by arranging the conduit 14 at an angle to the longitudinal direction of the support, and by disposing its gasket in a vertical plane at a full right angle to the longitudinal direction of the support.

angle to the vertical plane occupied by the gasket 34 in the conduit G.

What I claim is:

1. An automatic train pipe connector head comprising, in combination, a vertically arranged obliquely disposed base, centering means at opposite ends of said base and facing in a direction normal to the plane of the base, and primary guiding means separate from and below said 10 centering means and projecting forwardly of said base.

2. An automatic train pipe connector head comprising, in combination, a vertically arranged base, primary guiding means lying entirely below 15 the horizontal center of said base and extending forwardly and flaring laterally therefrom, and secondary or supplemental guiding means on opposite sides of the vertical center of said base and facing in a direction normal to the plane of the 20 base.

3. An automatic train pipe connector head comprising, in combination, a vertically arranged obliquely disposed base constructed to constitute in itself lateral guiding means for said head, a forwardly extending vertically flaring guiding prong secured to the lower side of said base and having a vertically disposed edge extending forwardly from the bottom of the base at substantially the center thereof, and secondary guiding means arranged at opposite ends of said base and facing in a direction normal to the plane of the base.

4. An automatic train pipe connector head comprising, in combination, a vertically arranged base adapted to guide the head laterally in one direction only, a forwardly extending prong secured to said base and adapted to guide the head laterally in the opposite direction only, said prong extending a substantial distance forwardly from the base at substantially a right angle to the base 40 and thence flaring laterally, and secondary guiding means arranged in opposite corners of said base and above the aforementioned prong to bring opposing heads into final register.

5. An automatic train pipe connector head comprising, in combination, a vertically arranged obliquely disposed oblong base, centering means at opposite ends of said base, and a forwardly extending downwardly inclined laterally flaring guiding prong on one side of the vertical center 50 of said head, said centering means comprising a bifurcated seat on one side of the vertical center of said base and a part-spherical member on the other side of said vertical center, the latter being adapted to rest in said seat of an opposing coupling head.

6. An automatic train pipe connector head comprising, in combination, a vertically arranged obliquely disposed substantially flat oblong base approximately one-half of which projects forwardly from the vertical center of the base and the other half of which retreats rearwardly from such center, the lower edge of the forwardly extending portion of the base being inclined upwardly to form a guide for vertical shifting of the head under certain conditions of disalignment, a prong secured to the lower side of said base on that side of said center which is opposite to the side occupied by said guide, said prong extending forwardly of the base at a right angle thereto and adapted under some conditions to co-act with said guide to align opposing coupling heads, and centering means on opposite sides of the vertical center of said head for securing final accurate register of mating heads.

7. An automatic train pipe connector head

comprising, in combination, a vertically arranged obliquely disposed base, centering means on opposite sides of the vertical center of said base and facing in a direction normal to the plane of the base, and a single guiding prong projecting forwardly from the lower edge of said base and flaring downwardly and serving to lift an opposing head and guide it laterally in one direction only.

8. An automatic train pipe connector head comprising, in combination, a vertically arranged base provided with an opening substantially at its center, a housing partly surrounding said opening and extending away from the rear side of said base, a forwardly extending downwardly inclined guiding prong secured to the lower side 15 of said base on one side of the vertical center of the base, a second housing secured to said base and having a front face disposed in a vertical plane at a right angle to the vertical plane occupied by said base, a conduit in each of said housings, each said conduit being provided with a gasket which occupies vertical planes at a right angle one to the other, means for preventing damage to said gaskets when opposing heads couple, and means for removably securing said 20 conduits in said housings.

9. An automatic train pipe connector head comprising, in combination, a vertically arranged base, centering means on opposite sides of the vertical center of said base, a guide below said 30 centering means and carrying a housing the front face of which is disposed in a vertical plane at a right angle to the vertical plane occupied by said base, a conduit in said housing, and thrust means supported from the under side of said guide and 35 adapted to shift said conduit along said housing.

10. An automatic train pipe connector head comprising, in combination, a vertically arranged base, centering means on opposite sides of the vertical center of said base, a guide below said 40 centering means having a primary guiding function for causing coaction of the said centering means and carrying a housing the front face of which is disposed in a vertical plane at a right angle to the vertical plane occupied by said 45 base, a conduit in said housing, and thrust means supported from the under side of said guide and adapted to shift said conduit along said housing, said thrust means including a plurality of bearings, a shaft mounted in said bearings, 50 means for preventing rotation of the shaft in the bearings, and a member threadingly mounted on said shaft to shift the shaft along said bearings.

11. An automatic train pipe connector head 55 comprising, in combination, a vertically arranged obliquely disposed oblong base, centering means on opposite sides of the vertical center of said base, said means comprising a part-spherical member protruding slightly from said base and 60 an annular seat for said member comprising a plurality of inwardly extending lugs, a primary guiding member below said centering means having a primary guiding function for causing coaction of the said centering means and projecting 65 forwardly of said base and adapted under certain conditions to engage the under side of one end of said base, means to prevent undue rotation of said coupling head when said guiding means and said base engage as stated, a fluid conduit 70 supported from the under side of said primary guiding means, the front face of said conduit being disposed in a plane at a right angle to the vertical plane occupied by said base, and bearings extending through said base and adapted to 75

receive a lock for anchoring said heads together, the longitudinal direction of said bearings being parallel to the plane occupied by the front face of said conduit.

- 5 12. An automatic train pipe connecter head comprising, in combination, a vertically arranged base disposed at an angle to the axis of the head and inclining rearwardly from a foremost outer end to a rearmost inner end, said base being 10 equipped with final guiding centering means adjacent to its foremost and rearmost ends, and a primary guiding member projecting forwardly from the base entirely at one side of a vertical plane intersecting the axis of the head and adapt- 15 ed to effect a preliminary guiding action of mating connecter heads for bringing the guiding centering means aforesaid into play for final accurate cooperation with corresponding means upon an opposite connecter head.
- 20 13. An automatic train pipe connecter head comprising, in combination, a vertically arranged

base disposed at an angle to the axis of the head and inclining rearwardly from a foremost outer end to a rearmost inner end, said base being equipped with final guiding centering means adjacent to its foremost and rearmost ends, and a primary guiding member projecting forwardly and downwardly from the base at one side of a vertical plane intersecting the axis of the head and adapted to effect a preliminary guiding action of mating connecter heads for bringing the guiding centering means aforesaid into play for final accurate cooperation with corresponding means upon an opposite connecter head, the said vertically arranged base having its lower edge extending substantially horizontally for some distance away from its primary guiding member aforesaid for cooperation with the upper portion of the primary guiding member of an opposed connecter head.

JOSEPH ROBINSON. 20
